UNITED STATES PATENT OFFICE.

EMERY D. VAN HORSEN, OF THREE FORKS, MONTANA.

SHAVING MUG.

Application filed January 3, 1923. Serial No. 610,481.

To all whom it may concern:

Be it known that I, EMERY D. VAN HORSEN, a citizen of the United States, and a resident of Three Forks, in the county of Gallatin and State of Montana, have invented a new and Improved Shaving Mug, of which the following is a full, clear, and exact description.

This invention has relation to containers 10 and refers more particularly to an improvement in shaving mugs which are especially designed for use in public barber shops.

The principal object of the present invention is to provide a mug or other open ended 15 receptacle of this type which is provided with means for maintaining the contents thereof in a heated condition. More specifically the invention contemplates a shaving mug of the character set forth which maintains a more even and agreeable temperature 20 to the brush and lather during the process of shaving the patrons of a barber shop, without adding extremely hot water from a faucet at frequent intervals during the time 25 required to shave one person.

As a still further object the invention contemplates a shaving mug which is comparatively simple in its construction, inexpensive to manufacture and which may be maintained in a thoroughly clean and sanitary 30 condition.

With the above recited and other objects in view, the invention resides in the novel construction set forth in the following specification, particularly pointed out in the appended claims and illustrated in the accompanying drawing, it being understood that the right is reserved to embodiments other 35 than those actually illustrated herein to the full extent indicated by the general meaning 40 of the terms in which the claims are expressed.

In the drawing—

Figure 1 is a vertical sectional view 45 through a shaving mug constructed in accordance with the invention.

Fig. 2 is a plan view thereof.

Referring to the drawing by characters of reference the mug consists of a holder 10 of 50 any desired configuration and a container unit 11 which is adapted to be concentrically supported within and spaced from the holder by suitable resilient embracing elements 12 which frictionally engage said container unit upon its insertion in the holder, 55 the holder being provided with the usual

handle 13. The container unit 11 consists of inner and outer shells 14 and 15 which define therebetween a sealed chamber 16 in which hot water or any other suitable heating agent 17 is placed through a filling opening 18 normally closed by a removable closure cap or plug 19. The lower portion 20 of the inner shell 15 is constructed of glass or any other suitable heat conducting material 60 while the upper portion 21 thereof and the entire outer shell 14 are constructed of a material or element which is a non-conductor of heat. In the present instance the portion 21 and the outer shell preferably consists of 65 inner and outer spaced layers 22 and 23 of metal between which a suitable packing 24 is disposed to reduce the dissipation of the heat of the heating agent therethrough, to a minimum. In practice, however, the packing 70 75 75 may be omitted if desired and a vacuum produced between the layers 22 and 23 to perform the same function.

In use, the hot water or heating agent 17 is introduced through the filling opening 18 80 into the chamber 16 and the closure plug 19 is replaced. As the mug is rinsed a new lather is made and at the beginning of each shave the lower portion 20 of the inner shell will be slightly raised in temperature, which 85 together with the radiation of the heat from the heating agent in the container unit, will maintain practically an unvarying temperature of the brush and lather for a period of time ordinarily required to shave a person. 90 When necessary the inner container unit 11 may be removed or withdrawn from the holder 10 for the purpose of cleansing the units.

I claim:

1. A shaving mug comprising spaced cup-shaped inner and outer shells connected at their upper ends and defining therebetween a sealed chamber for the reception of a heating agent, the entire outer shell and the upper portion of the inner shell constructed of a non-heat-conducting material, and the remaining lower portion of the inner shell constructed of a heat-conducting material, whereby to afford a container element, the 100 contents of which will be maintained in a heated condition from the heating agent through the portion constructed of conducting material and whereby the non-conducting portion will minimize the dissipation of 105 the heating agent.

2. A shaving mug comprising an outer

cup-shaped shell having an inturned and downwardly projecting flange at its upper open end, said shell consisting of outer, inner and intermediate layers constituting a heat insulating material and a relatively smaller cup-shaped member having its upper open end fitted between the inner and outer layers of the lower end of the flange, said inner member being constructed of a heat conducting material and said outer shell and mem-

ber defining therebetween a space for the reception of a heating agent whereby the contents of the mug within the inner cup-shaped member will be maintained in heated condition from the heating agent and whereby the outer shell will minimize dissipation of the heat from the heating agent through the outer sides of the mug. 15

EMERY D. VAN HORSEN.
